UNITED STATES PATENT OFFICE.

JAMES H. NORTHROP, OF TUSTIN, CALIFORNIA, ASSIGNOR TO DRAPER COMPANY, OF HOPEDALE, MASSACHUSETTS, A CORPORATION OF MAINE.

SELF-THREADING LOOM-SHUTTLE.

SPECIFICATION forming part of Letters Patent No. 690,177, dated December 31, 1901.

Application filed August 5, 1901. Serial No. 70,879. (No model.)

To all whom it may concern:

Be it known that I, JAMES H. NORTHROP, a citizen of the United States, and a resident of Tustin, county of Orange, State of California, have invented an Improvement in Self-Threading Loom-Shuttles, of which the following description, in connection with the accompanying drawings, is a specification, like letters on the drawings representing like parts.

This invention has for its object the improvement in loom-shuttles whereby pinching of the running thread when the shuttle is in use and consequent severance of the thread will be obviated.

The usual loom-shuttle is provided with an external longitudinal groove or recess extended along one side of the shuttle-body from the thread-delivery eye to receive the thread and to prevent the latter from being pinched between the side of the shuttle-body and the wall of the shuttle-box. So long as the thread lies properly in such groove there is no opportunity for pinching; but the weight of the thread and the direction of pull will often tend to lower it, so that it will be caught between the front wall of the shuttle-box and the side of the shuttle, above or below the groove. In my present invention I have provided the shuttle with a side thread-delivery eye located adjacent the bottom of the shuttle, and I have also shown the thread-groove located on the side of the shuttle-body adjacent the bottom thereof, so that if the thread drops it cannot be caught, as it merely drops onto the bottom of the shuttle-box.

Figure 1 is a top or plan view of a well-known form of loom-shuttle having my invention applied thereto. Fig. 2 is a side elevation thereof, showing the thread-delivery eye and the thread-groove adjacent the bottom of the shuttle-body. Fig. 3 is a transverse sectional view on the line $x-x$, Fig. 1, looking to the left, to show more clearly the thread-groove, the section being on a larger scale.

I have herein shown my invention as applied to an automatic self-threading shuttle, substantially such as shown and described in United States Patent No. 574,864, granted January 5, 1897. The shuttle-body A, the filling carrier or bobbin B, having the rings a at its base, the holding-jaws C, and the automatic self-threading device D may be and are substantially as in the patent referred to, the

threading device being provided with a longitudinal thread-entrance d' , (see Fig. 1,) having at one side a horn d^2 , a space d^4 being left beneath the outer end of the horn and the top of the shuttle-body to conduct the thread through a downwardly-inclined slot d^5 to the thread-delivery eye e . As shown in Fig. 2, the thread-delivery eye is located adjacent the bottom of the shuttle-body, so that the thread instead of being delivered from the side of the shuttle substantially midway between the top and bottom thereof is delivered at or near the bottom.

A longitudinal thread-groove h (see Fig. 2) is formed in the outer face of one of the side walls of the shuttle, leading from the delivery-eye e toward the opposite end of the shuttle, the groove being located adjacent the bottom of the shuttle. By reference to Fig. 3 it will be seen that the groove is formed by the overhanging shoulder h^x , so that if the thread drops it will drop onto the bottom of the shuttle-box and cannot be pinched between the front plate thereof and the side face of the shuttle.

By the "longitudinal axis of the shuttle" I mean a line extended longitudinally through the shuttle from one to the other point thereof.

I have herein shown my invention as applied to a shuttle provided with an automatic threading device; but my invention is not restricted to such application, as it may be used in connection with other types of loom-shuttles.

Having fully described my invention, what I claim as new, and desire to secure by Letters Patent, is—

1. A loom-shuttle rectangular in cross-section and having a thread-delivery eye in its side, and a longitudinal thread-groove on the shuttle side at the bottom thereof, leading from the eye.
2. A loom-shuttle, rectangular in cross-section and having an automatic self-threading device, and a thread-delivery eye in the side of the shuttle and adjacent the bottom thereof.

In testimony whereof I have signed my name to this specification in the presence of two subscribing witnesses.

JAMES H. NORTHROP.
